UNITED STATES PATENT OFFICE

2,452,822

REFLECTOR

James M. Wolf, Boston, Mass., assignor, by mesne assignments, to the United States of America as represented by the Secretary of War

Application April 28, 1944, Serial No. 533,234

2 Claims. (Cl. 343—18)

1

This invention relates to a reflector, and more particularly to an energy reflector adapted for use with radio echo detection systems to define the corners and boundaries of airports and the like.

The principal object of the invention is to provide a simple and inexpensive reflector of this character which may be easily assembled and disassembled, and which may be carried or stored in flat sections when not in use.

A reflector constructed in accordance with the present invention has three plane reflecting sheets, each sheet disposed at right angles to the other two. Energy rays striking any one of the sheets will reflect therefrom and from either or both of the other two sheets, the reflected rays being in a direction parallel to the incidence rays.

In the drawing, Fig. 1 is a plane view of the individual components of the reflector, and Fig. 2 is a perspective view of the assembled reflector.

Referring to Fig. 1 of the drawing, one plane surface of the reflector comprises supporting sheet 5, preferably rectangular or square in shape, having perpendicular apertures or slits 6 and 7 which intersect in the central portion of the sheet. Slits 6 and 7 terminate in enlarged ends 8, 9, 10, and 11 just short of the edges of sheet 5.

Two cooperating plane sheets 15, which when assembled intersect at right angles both with each other and with sheet 5, are provided. Sheet 15, also preferably rectangular or square in shape, has a slit 16 extending from the center thereof to an edge. Two shorter slits 17 and 18 oppositely extend inwardly from the midpoints of the sheet edges which parallel aperture 16. The length of slits 17 and 18 corresponds to the distance the ends of apertures 6 and 7 of sheet 5 are short of their respective edges.

The reflector is assembled by folding portions 19 and 20 of sheet 15 along the indicated dotted lines. Sheet 15 then is inserted in, for example, aperture 7 of sheet 5. Slit enlargements 8 and 11 of the aperture are of suitable size to receive the folded portions 19 and 20 of sheet 15. When the two pieces have thus been assembled, folded portions 19 and 20 may be returned to their unfolded position to lock the pieces against separation.

Second sheet 15 is prepared for assembly by folding portions 21 and 22 along their indicated dotted lines. Slits 16 in the two pieces 15 cooperate to permit perpendicular interfitting of the two sheets so that second sheet 15 may be received in aperture 6 of sheet 5. Similarly, the folded portions 21 and 22, which have passed through slit enlargements 8 and 10, may be returned to their unfolded position to secure the second sheet 15 in the assembly.

2

The assembled reflector, shown in Fig. 2, thus presents three perpendicular plane surfaces to incidence rays striking the reflector at any angle. Therefore, rays parallel to the incidence rays will be reflected from the device regardless of the vertical and horizontal angles of incidence.

The three sheets of the reflector may be made of metal, or they may be made of cardboard or some lighter material, if desired. A coating of metallic foil or conducting paint may be applied to the reflecting surfaces if cardboard is used.

It will be seen that this invention provides a simple, convenient, and effective reflector which may be carried flat and which may be easily and quickly assembled or disassembled. Having thus described the invention, what I claim as new and desire to secure by Letters Patent is:

1. An energy reflector having associated sheets presenting perpendicular plane surfaces to incidence rays whereby rays parallel thereto are reflected regardless of incidence ray direction, said reflector comprising a supporting sheet having centrally intersecting perpendicular slits therein which terminate short of the sheet edges, and two cooperating sheets perpendicular to each other and to said supporting sheet, said cooperating sheets each having a slit extending from its center to an edge whereby the sheets may be interfitted to be received in said perpendicular slits of said supporting sheet, and means for holding said supporting sheet to said interfitted sheets, said sheets having energy reflecting surfaces.

2. An energy reflector having associated sheets presenting perpendicular plane surfaces to incidence rays whereby rays parallel thereto are reflected regardless of incidence ray direction, said reflector comprising a supporting sheet having centrally intersecting perpendicular slits therein which terminate in enlarged ends short of the sheet edges, and two cooperating sheets perpendicular to each other and to said supporting sheet, said cooperating sheets each having a slit extending from its center to an edge whereby the sheets may be interfitted, said sheets also having slits extending inwardly from the midpoints of the edges parallel to said first named slit, said last named slits interfitting with said supporting sheet, each of said sheets having energy reflecting surfaces.
